201,465

SIZE PRESS OR SIMILAR ARTICLE

Lawrence Augustus Moore, Beloit, Wis., Joseph E. Peter, Cincinnati, Ohio, and Huston M. Broyles, Rockford, Ill., assignors to Beloit Iron Works, Beloit, Wis., a corporation of Wisconsin

Filed Dec. 22, 1961, Ser. No. 68,033

Term of patent 14 years

(Cl. D55—1)

FIG. 1

Des. 201,465

PAGE 2

~~FILED~~

~~FIG. 3~~ 3

FIGURE 1 is a perspective view of the front and one side of a size press or similar article embodying our new design;

FIGURE 2 is a perspective view of the front and opposite side thereof and taken from a position rotated approximately 180° from that shown in FIGURE 1; and

We claim:

The ornamental design for a size press or similar article as shown.
